UNITED STATES PATENT OFFICE.

PHILIP J. EVANS, OF MALAD CITY, IDAHO.

MEMORANDUM-CALENDAR.

1,222,612.

Specification of Letters Patent. Patented Apr. 17, 1917.

Application filed August 4, 1916. Serial No. 113,151.

To all whom it may concern:

Be it known that I, PHILIP J. EVANS, a citizen of the United States, and resident of Malad City, in the county of Oneida and State of Idaho, have invented certain new and useful Improvements in Memorandum-Calendars, of which the following is a specification.

The present invention relates to calendars and has particular reference to new and useful improvements in memorandum calen-dars.

The primary object of my invention is to provide a memorandum calendar affording space in which to place notes reminding the user of business engagements and the like.

Another object of my invention is to pro-vide a calendar of the class described having an arrangement of dates thereon practically identical with the standard calendar, with the exception that space is allowed at each date to place memorandum, this being my invention. The arrangement of dates is such that the calendar of my invention may be made up similar to the standard calen-dars now in use, very little more than the standard amount of space being occupied by my improved calendar.

Other objects and advantages to be de-rived from the use of my improved memo-randum calendar will appear from the fol-lowing detail description and the claims, taken with an inspection of the accompan-ying drawing, in which:

The figure represents in plan one month of a memorandum calendar embodying the improvements of my invention, the calendar consisting of twelve sheets as shown.

Referring more particularly to the draw-ing, wherein similar characters of reference designate like and corresponding parts, 1 designates one sheet of the body of a calen-dar, the same having the name of the month at the upper end thereof and the year, as well as the days of the week. The face of the sheet 1 is divided into a plurality of memorandum spaces 2 by means of vertical and horizontal parallel arranged intersecting lines 3 and 4, respectively. In the upper left hand corners of the spaces 2 I provide date spaces 5 in which the numbers of the days of the months are placed.

In using my improved memorandum cal-

endar it will be seen that business engage-ments and important matters to be attended 55 to at future times may be placed in the memorandum spaces 2, both the day and the date appearing at the most desirable point. My improved memorandum calendar will be found particularly useful to lawyers, real 60 estate men and others desiring to be re-minded of future business as the same should be attended to.

Of course, I do not limit myself to the exact location of the date number of spaces 65 5, since the same may be located in the lowermost corners or in the upper right hand corner, or at any point within the memorandum spaces.

From the above description taken in con-70 nection with the accompanying drawing, it is thought that a clear and comprehensive understanding of the construction, opera-tion and advantages of my invention may be had, and while I have shown and described 75 the device as embodying a specific struc-ture, I desire that it be understood that such changes may be made in said structure as do not depart from the spirit and scope of the invention as claimed.

Having thus fully described my invention, what I claim as new and desire to secure by Letters Patent, is:—

1. In a memorandum calendar, the combi-nation of a sheet having vertical and hori-zontal parallel arranged intersecting lines 85 thereon forming memorandum spaces, means for indicating the days of the week arranged at the upper end of the sheet, and numbers indicating the days of the month arranged 90 in certain of the corners of said memoran-dum spaces.

2. In a memorandum calendar, the combi-nation of a sheet having vertical and hori-zontal parallel arranged intersecting lines 95 thereon forming squares for memorandum spaces, means for indicating the days of the week arranged at the upper end of the sheet, smaller blocks formed in one of the upper corners of said blocks, portions of the sides 100 of said larger blocks forming sides for the smaller blocks, the smaller blocks providing spaces for indicating the days of the month.

In testimony whereof, I affix my signature hereto.

PHILIP J. EVANS.

Copies of this patent may be obtained for five cents each, by addressing the "Commissioner of Patents, Washington, D. C."
